W. VAN B. THOMAS.
SELF OILING GOVERNOR.
APPLICATION FILED APR. 5, 1919.

1,352,850.

Patented Sept. 14, 1920.

UNITED STATES PATENT OFFICE.

WILFRED VAN BUREN THOMAS, OF CATSKILL, NEW YORK.

SELF-OILING GOVERNOR.

1,352,850.

Specification of Letters Patent. Patented Sept. 14, 1920.

Application filed April 5, 1919. Serial No. 287,811.

To all whom it may concern:

Be it known that I, WILFRED VAN BUREN THOMAS, a citizen of the United States, residing at Catskill, in the county of Greene and State of New York, have invented new and useful Improvements in Self-Oiling Governors, of which the following is a specification.

This invention relates to self-oiling governors, and it consists in the novel features hereinafter described and claimed.

An object of the invention is to provide a governor mechanism with self-oiling means, whereby the disk of the governor may move freely on the stop or friction bar and upon the shaft and a sensitive governor is provided.

Another object of the invention is to provide a governor mechanism with self-oiling means, whereby the thorough lubrication of the friction speed control is had assuring an even, regular and uninterrupted speed and rotation.

The self-oiling governor is especially designed to be used upon talking machines, as, for instance, dictating machines, phonographs, dictaphones, ediphones and the like.

The invention consists primarily in providing the disk of the governor mechanism with an inturned periphery or flange, and means for supplying a lubricant to the intermediate portion of the body of the disk and within the flange whereby the said lubricant may gravitate or trickle upon the disk and the shaft and lubricate the bearing between the disk and the shaft and the face of the stop or friction bar where it contacts the disk. The inturned periphery or portion of the disk prevents the lubricant from flying from the disk when the disk is rotating.

In the accompanying drawing:

Figure 1, is a side elevation of one form of the self-oiling governor with parts in section.

Fig. 2, is a transverse sectional view of the same on the line 2—2 of Fig. 1.

Figs. 3, 4 and 5, are detailed sectional views of modified forms of the disks and oiling means which may be employed in the governor mechanism.

The governor mechanism comprises a shaft 1, which may be located in the usual manner. A collar 2, is fixed to the shaft 1, and resilient arms 3, are attached at one end to the collar 2, and carry at their inter-

mediate portions weights 4, of usual pattern. The opposite ends of the arms 3, are fixed to the hub 5, and a disk 6. The disk 6, is splined upon the shaft 1, that is to say, 60 that this disk may slide along the shaft but is constrained to rotate in unison with the same by means of the key 7, which is fixed to the shaft 1, and which is slidably received in the hub 5. Therefore, it will be 65 seen that after the shaft 1 rotates, the weights 4, are spread upon by centrifugal force, and the arms 3, are bowed outwardly whereby the hub 5, and disk 6, are drawn toward the collar in the usual manner. 70

In the form of the invention as illustrated in Figs. 1, 2, 4 and 5, the disk 6 is provided at its periphery with an inturned annular flange 8, in which is placed a lubricant for lubricating the stop or friction or speed 75 control bar 12, and as shown in Fig. 1, the hub 5, may be provided with one or more apertures 9, each of which may carry a wick 10. A post 11, is located adjacent to the upper portion of the disk 6, and may be mounted upon a fixed support (not shown). The stop or friction bar 12, is carried at the lower end of the post 11, and extends to the edge of the flange 8, and its inner end in the vicinity of the side of 80 the disk 6, but normally spaced therefrom. The stop or friction bar 12, may be a tube and have connected an oil cup 13, carried at the outer end of the tube 12, to further supply lubrication. 90

Therefore, as the disk 6, is moved toward the collar 2, the body portion of the disk will come in contact properly lubricated with the end of the friction speed control bar 12, causing equal friction and producing an even and uninterrupted speed and rotary movement of the disk 6, and the shaft 1, is checked and governed in a usual manner. At the same time the lubricant may flow from the oil cup 13, through the tube 100 12, and deposit a further supply of lubricant to the friction speed control bar 12, and upon the sides of the disk 6. The lubricant is prevented from being thrown off from the periphery of the disk by the flange 8, and the lubricant gravitates down lubricating the face of the disk 6, and saturates the wicks 10, and passes through the aperture 9, and lubricates the bearing between the hub 5, and the shaft 1, whereby the disk 6, 110 may move freely and regularly upon the shaft.

In the form of the invention as illustrated in Fig. 5, of the drawing, the oil cup 13, is attached directly to the intermediate portion of the disk 6, and in this case the usual friction speed control 12 is used.

In the form of the invention as illustrated in Fig. 3, the disk 6, is provided with an annular groove 14, which may receive the end portion of the member 12, whereby the oil or lubricant is deposited in the groove 14 and by gravitation lubricates the stop or friction speed control bar 12, and may gravitate from the groove 14 through a provided duct 16, to the bearing between the hub of the disk and the shaft.

In the form of the invention as illustrated in Fig. 4, of the drawing, the intermediate portion of the disk 6, is thickened as at 15, and the said thickened portion is provided with ducts 16, through which the oil may pass from the periphery or portion of the disk to the bearing between the hub of the disk and shaft.

In all forms of the invention, it will be observed that a simple and efficient oiling or lubricating means is provided for lubricating the friction speed control bar and the point of contact and the bearing between the disk and shaft of a governor mechanism and in all forms means are provided for preventing the oil or lubricant from being thrown by centrifugal force from the edge of the disk while the same is rotated.

While I have shown and described the preferred embodiment of my invention, it will be understood that minor changes in construction, combination and arrangement of parts may be made, to suit practical

conditions, provided such alterations are comprehended within the scope of the invention and what is claimed.

Having described the invention, what is claimed is:

1. A self-oiling governor comprising a shaft, a disk slidably mounted thereon and constrained to rotate with the same, means adapted to be operated by centrifugal force for moving the disk, a brake means or friction speed control adapted to be lubricated and engaged by the disk, said disk being provided with means for preventing the lubricant from flying from the same by centrifugal force and means for supplying a lubricant to the disk and friction speed control.

2. In a device as described, a shaft, a disk slidably mounted thereon, means for sliding the disk, said disk having an in-turned periphery or flange, a tube located within the flange and having an instep to be engaged by the disk and means for supplying a lubricant to the tube and disk.

3. In a device as described, a disk, a shaft upon which the disk is slidably mounted, means for moving the disk upon the shaft, said disk having a hub provided with an aperture, a wick located in the aperture, said disk having an in-turned periphery or flange and means for supplying a lubricant to the intermediate portion of the disk.

In testimony whereof, I affix my signature in presence of two witnesses.

WILFRED VAN BUREN THOMAS.
